Primary Examiner — Jack Reickel*Assistant Examiner* — Salamah Jordan(74) *Attorney, Agent, or Firm* — POLSON
INTELLECTUAL PROPERTY LAW, PC; Margaret Polson(57) **CLAIM**

The ornamental design for a training apparatus, as shown and described.

DESCRIPTION

FIG. 1 is an isometric view of our new training apparatus.

FIG. 2 is a front side elevation view thereof.

FIG. 3 is a back side elevation view thereof.

FIG. 4 is a right side elevation view thereof.

FIG. 5 is a left side elevation view thereof.

FIG. 6 is a top view thereof; and,

FIG. 7 is a bottom view thereof.

The features shown in broken lines in the drawings depict environmental subject matter only, and form no part of the claimed designs.

1 Claim, 7 Drawing Sheets(56)
